GRINDING MACHINE

Frederick P. Hess, Philadelphia, Pa., assignor to
The Enterprise Manufacturing Company of
Pennsylvania, Philadelphia, Pa., a corporation
of Pennsylvania

Application February 6, 1936, Serial No. 62,699

8 Claims. (Cl. 83—8)

This invention relates to new and useful improvements in grinding mills and more particularly to mills of the character generally used in grinding coffee, spices, and the like.

5 The principal object of the present invention is to provide a grinding mill of the character set forth having novel means automatically operable to permit the mill to continue in operation only so long as there is any material therein to be ground, thus eliminating the likelihood of undue wear and damage which may result to the faces of the grinding elements should the same be allowed to continue in operation after the material has been ground.

10 A more specific object of the present invention is to provide a switch controlled motor driven grinding mill of the type described having novel means automatically operable to maintain the switch in closed relation to operate said mill during grinding and immediately thereafter effect the opening of said switch to stop the mill.

15 These and other objects of the invention and the details of construction thereof are set forth hereinafter and shown in the accompanying drawing in which:

Fig. 1 is a sectional elevation of a grinding mill embodying the present invention.

20 Fig. 2 is a fragmentary end elevation of the lower portion of the disclosure in Fig. 1; and

25 Fig. 3 is a diagrammatic view of the electric circuit employed in carrying out the invention.

30 Referring now more particularly to the drawing, reference numeral 1 designates generally the body or casing of a grinding mill having a hopper 2 controlled by a gate 3 to an inlet 4 and an outlet 5 for the ground material. A rotating grinding disk 6 is secured by means of screws 7 to the inner face of a flange 8 which projects radially from a sleeve 9 slidably mounted on a shaft 10 for rotation therewith by means of a key 11, said shaft 10 being connected in direction with respect to said Fig. 2 and retain to an electric motor or other drive means 12. The right hand end of the sleeve 9 with respect to Fig. 1 of the drawing is helically threaded as indicated at 13 for the purpose of conveying

35 the material from the inlet 4 to a point between the grinding disk 6 and a second grinding disk 14. A spring 15 is disposed between a shoulder 16 on the inner wall of the sleeve 9 and the adjacent inner face of a transversely extending plate 17 secured to the inner end of the shaft 10 by means of a screw 18 and tends to force the grinding disk 6 away from the grinding disk 14.

40 The aforementioned second grinding disk 14 is

mounted upon the inner face of a flange 19 in parallel spaced relation with respect to the grinding disk 6. In the present instance the flange 19 projects radially from a sleeve 20 and extends to the adjacent inner wall surface of the mill casing 1 to insure passage of the material to be ground between the relatively opposed grinding disks 6 and 14 respectively. As shown in the drawing, the sleeve 20 is mounted in coaxial outwardly spaced relation with respect to the sleeve 9 and shaft 10 and is arranged for relative axial movement with respect to the latter for the purpose of adjusting the grinding disk 14 with respect to the grinding disk 6 to vary the fineness of the grinding operation, adjustment of said sleeve 20 being effected by means of a screw 21 actuated by a sleeve cap 22 located externally of the mill casing 1.

45 As shown in Fig. 1 of the drawing, a pin 23 is fixedly mounted in the flange 19 of the sleeve 20 and projects laterally outwardly therefrom freely through an arcuate slot or opening 24 formed in the adjacent wall of the casing 1 to positively restrict rotation of said flange 19 and grinding disk 14 within the limits afforded by said slot or opening 24. An electric switch 25 connected in the circuit of the motor 12 is mounted externally of the mill casing 1 below the slot or opening 24 so that the operating arm or lever 26 thereof projects upwardly into the limited path of movement of the aforementioned pin 23. The switch 25 is preferably of a standard type constructed and arranged so that a spring 27 therein tends to force the operating arm or lever 26 to the position shown in solid lines in Fig. 2 to open the motor circuit and stop the mill; and a second spring 28 connected to the pin 23 at the extreme right-hand end of the slot or opening 24.

50 Referring particularly to Fig. 2 of the drawing, it will be observed that in order to operate the mill for grinding it is necessary that the grinding disk 6 and a second grinding disk 14 be actuated to 45 the left and held in the position shown in dotted lines against the combined action of the springs 27 and 28 for the duration of the grinding operation. This is accomplished in the present instance by the rotary grinding action of the disk 6 upon the material being ground which exerts a corresponding rotative force upon the grinding disk 14 sufficient to retain the pin 23 and switch 55

arm 26 in the aforementioned relationship. On the other hand, it will be obvious that substantially simultaneously with passage of the last of the material outwardly from between the 5 grinding disks 6 and 14 the springs 27 and 28 will actuate the switch arm 26 and pin 23 into the relative positions shown in solid lines in Fig. 2 of the drawing to open the switch and stop the mill.

10 In operation of a grinding mill embodying the present invention, coffee, spices or other material is placed in the hopper 2 and the gate 3 opened so that said material passes through the inlet 4 ready to be conveyed to the grinding disks 15 6 and 14 by the threads 13 on the sleeve 9. To start operation of the mill the pin 23 and switch arm or lever 26 are actuated manually or by means of a lever into the position shown in dotted lines in Fig. 2 to close the switch 25, the 20 pin 23 being held in this position for several seconds of time to allow the grinding disk to come up to speed and begin to grind the material. Manual control of the pin 23 may then be relinquished and the aforementioned rotative force 25 exerted upon the disk 14 by the action of the grinding disk 6 upon the material being ground will retain said pin 23 and switch arm 26 in the position to which actuated until the last of the material to be ground has passed outwardly from 30 between the grinding disks 6 and 14 at which time the spring 28 and the switch spring 27 immediately actuate said pin 23 and switch arm 26 to the right as shown in solid lines to open the switch and stop the mill.

35 While the foregoing description of the invention includes a discussion of the construction and operation of the spring 28 connected between the flange 19 and adjacent wall portion 29 of the casing 1, it is pointed out that said spring 40 28 is not necessary to the successful operation of the mill in accordance herewith and may be wholly eliminated so long as the spring 27 of the motor switch 25 is sufficient to return the switch lever 26 and the pin 23 as well as its associated 45 mechanism to the inoperative position shown in solid lines in Fig. 2 at the completion of a grinding operation, and although the present description is otherwise limited to a specific embodiment of the invention, it is not intended that 50 said invention be precisely limited thereto but that changes and modifications may be made in the details of construction within the scope of the annexed claims.

I claim:

55 1. In a grinding mill of the character described, a rotatable grinding disk, means movable with said grinding disk, a switch located in the path of travel of said last mentioned means, means tending to open the switch, a motor controlled 60 by said switch, and a second grinding disk having driving connection with said motor arranged with respect to the first grinding disk so that when the first mentioned means is actuated to close the switch to start the motor, the action 65 of the second grinding disk and material being ground upon the first grinding disk functions to retain said first mentioned means in the position to which actuated to maintain said switch closed for the duration of the grinding operation.

70 2. In a grinding mill of the character described, a rotatable grinding disk, means movable with said grinding disk, a switch located in the path of travel of said last mentioned means, means tending to open the switch, a motor controlled by 75 said switch, a second grinding disk having driv-

ing connection with said motor arranged with respect to the first grinding disk so that when the first mentioned means is actuated to close the switch to start the motor, the action of the second grinding disk and material being ground upon the first grinding disk functions to retain said first mentioned means in the position to which actuated to maintain said switch closed for the duration of the grinding operation, and means operable without interfering with the control and operation of the switch for adjusting the first mentioned disk with respect to the second disk to vary the degree of fineness of the grind. 5

3. In a grinding mill of the character described, 15 a rotatable grinding disk, means movable with said grinding disk, a switch, an operating lever for said switch movable in the path of travel of said last mentioned means, means acting on said operating lever tending to open the switch, a 20 motor controlled by said switch, and a second grinding disk having driving connection with said motor arranged in parallel spaced relation with respect to the first grinding disk so that when the first mentioned means is actuated to engage 25 the operating lever and close the switch to start the motor, the action of the second grinding disk and material being ground upon the first grinding disk functions to retain said first mentioned means in the position to which actuated to maintain 30 said switch closed for the duration of the grinding operation.

4. In a grinding mill of the character described, 35 a rotatable grinding disk, means movable with said grinding disk, a switch, an operating lever for said switch movable in the path of travel of said last mentioned means, means acting on 40 said operating lever tending to open the switch, a motor controlled by said switch, a second grinding disk having driving connection with said motor arranged in parallel spaced relation with respect to the first grinding disk so that when the first mentioned means is actuated to engage the operating lever and close the switch to start the motor, the action of the second grinding disk 45 and material being ground upon the first grinding disk functions to retain said first mentioned means in the position to which actuated to maintain said switch closed for the duration of the grinding operation, and means operable without 50 interfering with the control and operation of the switch for adjusting the first mentioned disk with respect to the second disk to vary the degree of fineness of the grind. 55

5. In a grinding mill of the character described, 55 a grinding disk rotatable within predetermined limits, means movable with said grinding disk, a switch located in the path of travel of said last mentioned means, springs respectively tending to open the switch and maintain the grinding disk 60 and the first mentioned means at one limit of rotation, a motor controlled by said switch, and a second grinding disk having driving connection with said motor arranged in parallel spaced relation with respect to the first grinding disk so 65 that when the first mentioned means is actuated to close the switch to start the motor, the action of said second grinding disk and the material being ground upon the first grinding disk functions to retain said first mentioned means in 70 the position to which actuated against the action of the springs to maintain said switch closed for the duration of the grinding operation.

6. In a grinding mill of the character described, 75 a grinding disk rotatable within predetermined 75

limits, means movable with said grinding disk, a switch located in the path of travel of said last mentioned means, springs respectively tending to open the switch and maintain the grinding disk 5 and the first mentioned means at one limit of rotation, a motor controlled by said switch, a second grinding disk having driving connection with said motor arranged in parallel spaced relation with respect to the first grinding disk so that 10 when the first mentioned means is actuated to close the switch to start the motor, the action of said second grinding disk and the material being ground upon the first grinding disk functions to retain said first mentioned means in the 15 position to which actuated against the action of the springs to maintain said switch closed for the duration of the grinding operation, and means operable without interfering with the control and operation of the switch for adjusting the first 20 mentioned disk with respect to the second disk to vary the degree of fineness of the grind.

7. In a grinding mill of the character described, a grinding disk rotatable within predetermined limits, means movable with said grinding disk, a 25 switch, an operating lever for said switch movable in the path of travel of said last mentioned means, springs acting respectively on said operating lever tending to open the switch and on the grinding disk tending to maintain the latter and 30 the first mentioned means at one limit of rotation, a motor controlled by said switch, and a second grinding disk having driving connection with said motor arranged in parallel spaced relation with respect to the first grinding disk so that 35 when the first mentioned means is actuated to

engage the operating lever and close the switch to start the motor, the action of said second grinding disk and the material being ground upon the first grinding disk functions to retain said first mentioned means in the position to which actuated against the action of the springs to maintain said switch closed for the duration of the grinding operation. 5

8. In a grinding mill of the character described, a grinding disk rotatable within predetermined 10 limits, means movable with said grinding disk, a switch, an operating lever for said switch movable in the path of travel of said last mentioned means, springs acting respectively on said operating lever tending to open the switch and on the 15 grinding disk tending to maintain the latter and the first mentioned means at one limit of rotation, a motor controlled by said switch, a second grinding disk having driving connection with said motor arranged in parallel spaced relation with 20 respect to the first grinding disk so that when the first mentioned means is actuated to engage the operating lever and close the switch to start the motor, the action of said second grinding disk and the material being ground upon the first 25 grinding disk functions to retain said first mentioned means in the position to which actuated against the action of the springs to maintain said switch closed for the duration of the grinding operation, and means operable without interfering with the control and operation of the switch for adjusting the first mentioned disk with respect to the second disk to vary the degree of 30 fineness of the grind. 35
